M. MILLER

HARNESS FERRULE

Filed April 30, 1928

MELCHER MILLER,
INVENTOR.

BY *Harold Chapman*
ATTORNEY.

UNITED STATES PATENT OFFICE.

MELCHER MILLER, OF LEIPZIG, SASKATCHEWAN, CANADA, ASSIGNOR OF ONE-HALF
TO LUDWIG STIEFEL, OF LEIPZIG, SASKATCHEWAN, CANADA.

HARNESS FERRULE.

Application filed April 30, 1928, Serial No. 274,115, and in Canada March 28, 1928.

This invention relates to harness ferrules and particularly to a construction adapted to be used as an auxiliary fitting where straps are connected to rings of the harness.

5 The object of my invention is to provide an auxiliary member which can be fitted into the turned back portion of the strap members, which member will have an inner concaved contour curved at the same curvature as the 10 inner circumference of the ring to which the strap is to be attached.

A further object of my invention is in the method by which I retain the wearing portion 15 of my member in its proper position relative to the retainer portion.

With the foregoing and other objects in view, as will appear as the description proceeds, the invention consists of the novel construction, combination and arrangement of 20 co-operating elements as hereinafter more specifically set forth, claimed and shown in the accompanying drawings forming a part of the present application, in which:

Fig. 1 is a perspective view of the preferred 25 embodiment of my invention.

Fig. 2 is a side elevation showing a section of the ring as in position.

Fig. 3 shows a side elevation of the ring with the preferred embodiment of my invention, shown in cross section.

Like numerals of reference designate corresponding parts throughout the different views.

4 is a harness ring which may be of any size 35 adapted to the particular purpose for which it is to be used. 5 represents one of the strap members of the harness which has a looped back end 6. Under ordinary circumstances, if the looped end 6 is fitted through the ring 40 4, considerable wear is occasioned on the edges of the strap 5. To overcome this undesirable feature, I provide a wearing member 7, having a convexed, curved portion 8 designed to fit the curvature of the inner circumference of the ring 4. The outer face of

the wearing member 7 is rounded, as at 9, to adapt itself to the common curvature of the looped back end 6 of the strap 5. 10 is a retainer member suitably fitted over the rounded portion 9 and having extended opposite sides adapted to extend in parallel alignment with the sides of the looped end portion 6 of the strap 5. These sides and the looped end portion 6 are provided with oppositely registering openings through which the rivet 11 is used to retain this auxiliary member in proper position.

Any desired means may be used for retaining the wearing member 7 in proper position in the retainer member 10. The curved portion may have tongues 12 cut therefrom and bent inwardly at an inclined angle and imbedded in the wearing member 7 either after or during the forming of the same in the retainer member 10.

The foregoing specification and annexed drawings disclose the preferred embodiment of my invention, but it is to be understood that minor changes may be resorted to in the commercial adaptation of my invention without departing from the scope of the invention as hereinafter claimed.

What I claim as new is:

1. A harness ferrule comprising a wearing member, one face of which is of curved, convexed formation, the other face being of rounded formation and a retainer member engageable over the rounded face and adapted to be suitably connected in a strap loop.

2. A harness ferrule comprising a wearing member, one face of which is of curved, convexed formation, the other face being of rounded formation; a retainer member engageable over the rounded face and adapted to be suitably connected in a strap loop and a means fixedly retaining said wearing member in said retainer member.

In testimony whereof, I affix my signature.

MELCHER MILLER.
